UNITED STATES PATENT OFFICE.

ROBERT ALLEN, OF BURSLEM, ENGLAND.

DESIGN FOR AN EARTHENWARE PLATE OR SIMILAR ARTICLE.

SPECIFICATION forming part of Design No. 35,324, dated November 26, 1901.

Application filed May 6, 1901. Serial No. 59,065. Term of patent 3½ years.

To all whom it may concern:

Be it known that I, ROBERT ALLEN, a subject of the King of Great Britain and Ireland, residing at Burslem, England, have invented and produced a new and original Design for an Earthenware Plate or Similar Article, of which the following is a specification, reference being had to the accompanying drawing, forming part thereof.

10 The figure shown in the drawing represents the plan of a plate forming part of a dinner-service ornamented with my design. As shown therein, my design consists of a circular plate with sunk center portion and having on its rim a printed pattern of floral character, the leading feature of which is the repetition in regular sequence of the flower anem-

15

one with a surrounding ring of small ovals and an inner ring of graduated circles arranged in festoons from the tips or leaves of 20 the flowers.

It is apparent that the design is also applicable to dishes, tureens, and other objects of a dinner-set.

Having described my invention, what I 25 claim as new, and desire to secure by Letters Patent, is—

The design for an earthenware plate or similar article as herein shown and described.

ROBERT ALLEN.
